UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,827, dated October 29, 1895.

Application filed September 27, 1895. Serial No. 563,941. Term of patent 3½ years.

To all whom it may concern:

Be it known that I, CHARLES Booz, a citizen of the United States, residing at Buffalo, in the county of Erie and State of New York, have invented and produced a new and original Design for Wall-Paper, of which the following is a specification, reference being had to the accompanying drawing, showing a part thereof.

- o The design consists of Romanesque style of ornaments formed of ornamental scrolls diverging right and left from a small circle containing a four-leaf rosette and a cone-shaped ornament or figure above said circle, as represented in the accompanying drawing. Said ornaments are placed at regular distances apart over the surface of the paper and a plain narrow band is arranged vertically on each side of said ornaments.
- o The border of the design is formed of a

series of lines and leaf-like scrolls forming a circular figure or ornament with a cone-shaped ornament in the center and pendent ornamental figures between said circular ornaments and connected with said circular ornaments by curved and straight lines, as shown in the drawing. A narrow horizontal band forms the top and bottom of said border.

What I claim is—

1. The design for wall paper herein shown and described.
2. In the design for wall paper the border herein shown and described.

Witness my hand this 24th day of September, 1895.

CHARLES BOOZ.
